UNITED STATES PATENT OFFICE,

JULIUS C. GOODWIN, OF PHILADELPHIA, PENNSYLVANIA.

SEWING-MACHINE.

No. 909,081.

Specification of Letters Patent.

Patented Jan. 5, 1909.

Original application filed September 14, 1905, Serial No. 278,428. Divided and this application filed December 31, 1907. Serial No. 408,819.

To all whom it may concern:

Be it known that I, JULIUS C. GOODWIN, a citizen of the United States, residing at Philadelphia, in the county of Philadelphia and State of Pennsylvania, have invented 5 certain new and useful Improvements in Sewing-Machines, of which the following is a specification.

My invention relates to improvements in 10 that class of sewing-machines employed in the making of shirts and underwear in which two or more chain stitches are produced by means of duplicate needles and thread-carrying loopers.

15 My improvements relate particularly to the mechanism for operating the needle-bar and thread carrying loopers, and the objects of the invention are to render this mechanism nearly free from lost motion tending to 20 set up unnecessary vibration by the employment of positive and direct movements which are at once simple and durable in construction and capable of meeting the demand for a high speed power driven machine for a special class of factory work.

In an application filed September 14, 1905, Serial No. 278,428 I have shown and described a similar machine as a whole, but as the stitch forming mechanism was held 30 to be an independent subject of invention, I herewith make separate application therefor.

In the accompanying drawing forming 35 part of this specification I have illustrated my improvements as applied to a special form of sewing machine; but it will of course be understood that my invention is adapted for use in connection with other types of sewing machine.

40 In the drawings, Figure 1 illustrates a front elevation of a sewing machine embodying my improvements. Fig. 2 represents a sectional plan view of the same taken on a line indicated at 2-2 in Fig. 1. Fig. 3 shows a 45 detached perspective view of a portion of the looper mechanism. Fig. 4 illustrates a similar view of portions of the looper mechanism detached and arranged in line of connection, and Fig. 5 shows a rear elevation

with a portion of the bed broken away better 50 to illustrate the internal mechanism.

Referring now in detail to the parts of the machine illustrated in the drawings.

A, indicates the base of the machine which as shown in Fig. 2 is provided with bearings 55 A¹, A¹ to support a main shaft B. This driving shaft is furnished with a hand wheel B¹, a grooved driving-pulley B² and a line of eccentrics B³, B⁴, B⁵, B⁶ and B⁷, from which power is obtained to operate the several parts of the machine in a manner hereinafter described. The base of the machine supports a curved arm A² in front of which are lugs or projections A³, and A⁴, for guiding a needle-bar C, and a presser-bar D. The 60 base as will be seen has also a projecting arm A⁵, hollowed out to receive a portion of a stitch forming mechanism together with a feeding mechanism and at its free end is furnished with a removable cover A⁶.

The needle-bar and its operating devices which I shall hereinafter refer to as the upper stitch forming mechanism, is controlled by the eccentric B³, after the following manner.

75 The eccentric B³, is provided with an eccentric rod C² which extends upward through an opening in the bed of the machine and is there connected by a stud to the lower arm of a bell-crank lever C³. The bell-crank 80 lever C³, is fulcrumed to the arm A², by means of a stud-bolt C⁴, and is connected to a crank-arm C⁶, by a connecting rod C⁵. The crank-arm C⁶, is firmly secured to a short shaft C⁷, supported in a bearing formed in 85 the front end of the arm A², which shaft after passing through the arm A², is connected on the front side of the machine to a counter-balance, lever C⁸. One end of the lever C⁸, is connected to a sleeve C¹¹, on the 90 needle-bar C, by means of a link C¹⁰, while the other end of the lever is enlarged as shown at C⁹, to furnish sufficient weight to counter-balance the weight of the needle-bar C, and its connections. The lower end 95 of the needle-bar C, is furnished with another sleeve C¹², provided with suitable openings to receive one or more needles C¹³, C¹³.

The presser-bar D, is provided with the conventional presser-foot D¹, which is normally pressed downward by means of a leaf-spring S, one end of which is fastened by a screw d, to the arm A², while the other bears upon a collar d¹, on the presser-bar D. The pressure of the spring S, may be increased or diminished by means of a thumb-screw D², which passes through a projection on the 10 spring and enters a threaded opening in the arm A².

The presser-bar D is raised and lowered by means of a lever D³, fulcrumed by a stud D⁴, on the arm A², and having one end operatively connected to the presser-bar, while the other end is provided with a rod d³, which passes down below the base of the machine and is adapted to be actuated by the foot of the operator. Within the arm or extension 20 A⁵, is a feeding mechanism comprising a bar E, controlled by the cams B⁶, and B⁷, the former of which directs the horizontal movement or feed proper, while the latter raises and lowers the mechanism to engage and disengage the work. The feed-bar E, at its working end is provided with a toothed feed-dog E¹, adjustably secured in position by a screw e¹, and at its opposite end directly connected to the eccentric B⁶.

30 The feed-bar E, is provided with a slot E², to receive a sliding block E³, to which the bifurcated members e³, e³, of a bell-crank lever E⁴, are operatively connected. The bell-crank lever E⁴, is fulcrumed to the bed A⁵, by 35 a stud e⁴, and is operated from the eccentric B⁷ by an eccentric-rod E⁵, interposed between the eccentric and a member e⁵, of the bell-crank lever.

The looper mechanism which constitutes 40 one of the essential features of my invention comprises a looper-bar F², guided in the bed A⁵, partly by said arm and partly by a guide member f². The looper-bar being thus guided is free to slide back and forth under 45 the control of the eccentric B⁴ and an eccentric-rod F⁵.

The looper-lever F, is constructed in the form of an adjustable bell-crank lever, one of the arms F¹ of which is provided with a set of 50 thread carrying loops f, f, which as is well known in the art are adapted to intercept the loops brought down by the upper or complementary stitch forming mechanism including in this instance the thread carrying needles 55 C¹³, C¹³.

The looper lever F, is fulcrumed to the looper-bar F², by a stud f¹, and is adapted to oscillate or move back and forth through the arc of a circle by means of the eccentric B⁵ 60 and an eccentric rod F³. The looper lever F, has an arm F¹¹, provided at its extremity with a ball f¹¹, which is adapted to a socket f¹⁰, in the end of the eccentric rod F³.

In order to adjust the position of the loops

ers f, f, with respect to the needles C¹³, C¹³, 65 the looper-lever F, is made in two parts, so that the arm F¹, may be moved about the stud f¹, without affecting the position of the arm F¹¹. To accomplish this the arm F¹¹, is provided with a split ring f¹², to receive a hub 70 f¹³, of the lever F¹, which when properly adjusted may be held in position by a screw f¹⁴, adapted to lugs on the split ring f¹².

Having described my invention what I claim and desire to secure by Letters Patent is:

1. In a sewing machine, the combination with the upper stitch forming mechanism, a looper-bar guided in the bed of the machine and adapted to move in a path parallel with the feed mechanism, a looper lever fashioned in the form of a bell crank and fulcrumed to the upper side of the looper bar, an auxiliary looper-rod connected to one arm of the looper-lever, a looper secured to the other arm thereof, an eccentric and eccentric rod for operating the looper-bar, and an eccentric for operating the auxiliary looper-rod.

2. In a sewing machine, the combination with the upper stitch forming mechanism, a looper-bar guided in the bed of the machine and adapted to reciprocate in a path parallel with the feed mechanism, a looper-lever mounted upon the looper-bar and adapted to oscillate upon a vertical axis, an auxiliary looper-rod operatively connected to the looper lever, an eccentric and eccentric rod for operating the looper-bar and an eccentric for operating the auxiliary looper-rod.

3. In a sewing machine, in combination with the lower stitch forming mechanism, a main shaft, an eccentric, a bell crank, mounted upon the arm of the machine, an eccentric rod operatively connected to the eccentric and to one of the arms of the bell crank, a 105 needle bar, a fulcrumed lever having one of its arms weighted to form a counter balance and the other connected to the needle-bar, and intermediate actuating mechanism in line of connection with the main shaft whereby said lever is operated.

4. In a sewing machine, the combination with the lower stitch forming mechanism including a thread carrying-looper, a main shaft, an eccentric, a bell crank lever mounted on the arm of the sewing machine, an eccentric rod operatively connected to the eccentric and to one of the arms of the bell-crank lever, a needle-bar provided with a thread carrying needle, a counter balance 120 lever fulcrumed to the arm of the machine and operatively connected to the needle-bar and a connecting rod interposed between the counter-balance lever and the other arm of the bell crank lever.

5. In a sewing machine, the combination with the lower stitch forming mechanism including a reciprocating looper-bar and oscil-

latory looper, a needle bar provided with a thread carrying needle, a counter balance lever operatively connected to the needle bar and fulcrumed to the arm of the machine, a 5 main shaft, an eccentric, a bell crank lever fulcrumed to the arm of the machine midway between the shaft and the needle bar, an eccentric rod leading from the eccentric to one of the arms of the bell crank lever, and a con-

necting rod leading from the other arm of the 10 bell crank lever to the counter balance lever substantially as set forth.

In testimony whereof I affix my signature in presence of two witnesses.

JULIUS C. GOODWIN
